DESIGN FOR A PERMANENT WAVING MACHINE

Conkling Chedister, Livingston, N. J., assignor to
Eugene, Ltd., Brooklyn, N. Y., a corporation of
New York

Application July 1, 1948, Serial No. 147,330

Term of patent 14 years

(Cl. D86—10)

To all whom it may concern:

Be it known that I, Conkling Chedister, a citizen of the United States of America, and resident of Livingston, county of Essex, State of New Jersey, have invented a new, original, and ornamental Design for a Permanent Waving Machine, of which the following is a specification, reference being had to the accompanying drawings, forming part thereof.

Figure 1 is a perspective view of a permanent waving machine showing my new design;

Figure 2 is a top plan view; and

Figure 3 is a side elevation of the machine shown in Figure 1.

I claim:

The ornamental design for a permanent waving machine, as shown.

CONKLING CHEDISTER.
